UNITED STATES PATENT OFFICE.

EDWARD O. COTTON, OF GOLDSBORO, NORTH CAROLINA, ASSIGNOR OF ONE-HALF TO
FREDERICK M. MOYE, OF GOLDSBORO, NORTH CAROLINA.

SIGN.

Application filed August 4, 1921. Serial No. 489,733.

To all whom it may concern:

Be it known that I, EDWARD O. COTTON, citizen of the United States, residing at Goldsboro, in the county of Wayne and

5 State of North Carolina, have invented certain new and useful Improvements in Signs, of which the following is a specification, reference being had therein to the accompanying drawing.

10 My invention relates to new and useful improvements in signs and more particularly to a sign adapted for attachment to an automobile, it being so constructed as to be easily read in the day time and adapted to 15 be illuminated so that it may be read at night.

The principal object of my invention resides in the provision of such a sign which is simple and inexpensive in construction 20 and of such a size that it may be easily connected to or disconnected from the automobile.

Another object of the invention consists in constructing the sign in such a manner 25 that it may be hooked over the edge of the automobile windshield or similar supporting member.

A further object consists in the provision of a removable transparent plate so that 30 different plates may be used to provide different reading matter for the sign and means for holding said plate tightly in position to prevent breaking or rattling.

The invention has for a still further object the construction of the sign with a switch in easy reach of the automobile operator so that the electric light, supported 35 in the sign, may be switched on or off at will.

40 With the above and other objects in view, which will appear as the description proceeds, my invention consists in the novel details of construction and arrangement of parts, described in the following specification 45 and illustrated in the accompanying drawings, and while I have illustrated and described the preferred embodiments of the invention it will be understood that such changes may be made as will fall within the 50 scope of the appended claims.

In the drawings:—

Fig. 1 is a front elevation.

Fig. 2 is a top plan.

Fig. 3 a horizontal section.

55 Fig. 4 a transverse vertical section.

Fig. 5 an end view, and

Fig. 6 a detail showing an end view of a removable end plate.

In the drawings the numeral 1 indicates a casing, open at the front and one end, 60 and preferably rectangular in shape as shown. A downwardly extending flange 2 is formed around the top edge of the front opening, an upwardly extending flange 3 around the bottom edge of the opening, and an inwardly extending flange 4 on the closed end, these flanges 2, 3 and 4 forming a bearing surface for a removable transparent plate 5 adapted for insertion through the open end of the casing. The open end of 65 the casing is formed with the inwardly extending rear flange 6 and top and bottom flanges 7 and 8 respectively, these flanges 6, 7 and 8 forming a guide for a removable end plate 9 having the outer end provided 70 with the inwardly extending flange 10 adapted to overlie the end of the transparent plate 5 which bears a suitable sign.

A reflector 11 is mounted in the casing and, as more particularly shown in Fig. 3, 80 has its ends curved outwardly as indicated at 12 so that the light will be properly reflected towards the transparent plate 5, the ends of said reflector being bent at right angles to form the rearwardly extending 85 arms 13 which engage the back of the casing for properly positioning the reflector therein. As will be noted by reference to Fig. 3 one end of the reflector terminates short of the open end of the casing so as to leave 90 a space for the removable end plate 9, the end of said reflector cooperating with the flanges 6, 7 and 8, of the casing, to form a guide for the removable end plate. The curved ends 12 of the reflector engage the 95 inner face of the transparent plate 5 and aid in supporting said plate in position in the casing.

Secured to the inner face of the reflector 11, adjacent both the top and bottom edges 100 thereof, are the spring fingers 14 which yieldably engage the inner face of the transparent plate 5 to press the same tightly against the flanges of the casing. These spring fingers hold the plate in such a manner as to prevent rattling and at the same time being yieldable will have a tendency to prevent breakage of the glass.

Longitudinally spaced hooks 15 are formed on the top front edge of the cas- 110

ing and are adapted to engage over the edge of the windshield or other suitable support. These hooks will preferably be provided on the inner face with a lining 16 of felt or similar material to prevent marring of the windshield or other support over which the hooks are engaged. As quite clearly shown these hooks extend beyond the face of the sign so that the said sign, 10 when in position upon a windshield, will engage the face of the shield so that the sign may be easily read therethrough.

For illuminating the sign I provide an exteriorly threaded sleeve 17 which passes 15 through the bottom of the casing and is secured thereto by the jam nuts 18, one of said nuts engaging the inner face of the bottom and the other nut engaging the outer face. A socket 19 is formed upon the 20 upper end of the sleeve to receive and connect the electric light bulb 20 the front face of which is preferably coated as shown at 21 to prevent light from shining therethrough, said coating also acting as a reflector for reflecting the light to the main 25 reflector 11. The sleeve 17 is provided, adjacent the lower end, with a transversely extending elongated slot 22 through which a switch operating lever 23 extends, within 30 easy reach of the automobile operator, so that the light may be switched on or off at will. The electric light wires 24 extend through the removable cap 25 and are connected to the contact points within the socket 35 19 in the usual manner. These wires 24 will tend to hold the bottom of the sign and with the hooks 15 will prevent displacement of the sign with respect to the windshield or other suitable support.

40 From the above detailed description it is thought that the construction and operation will be clearly understood. As previously stated my sign is primarily intended for use on automobiles but it will be appreciated 45 that it might equally as well be used in various other connections. The sign will be of particular advantage in connection with taxicabs or other automobiles for hire in that it may be positioned to be easily read to 50 show whether the automobile is vacant or "for hire." The transparent plate 5 may have any desired reading matter thereon, and as these plates are removable plates of different reading may be interchanged at 55 will. The hooks 15 form easy means for connecting the sign in position and the sign may be easily detached, at will, should it be desired to take the sign from view, such as when the automobile is occupied or "not 60 for hire." The switch lever 23 is positioned in easy reach of the operator of the automobile so that, as previously stated, the

light may be switched on or off at will. The sign may be easily read in the day time, without being illuminated, although of course, it will be understood, if desired, the light may also be switched on during the day.

Having fully described my invention what I claim as new and desire to secure by Letters Patent is:—

1. A sign comprising a casing open at the front and one end, a reflector mounted in the casing and having its ends bent to engage the rear wall of the casing, a transparent plate removably received in the casing over the front opening and in front of the reflector, and a removable plate for the open end of the casing, the end of the reflector, with the end of the casing, forming 75 a guide for said transparent plate, and the plate adapted to engage the end of the transparent plate for holding it within the casing.

2. A sign comprising a casing open at the front and one end, an inwardly extending flange formed around the top and bottom edge of the front opening and at the closed end, a guide-way formed at the open end of the casing, a reflector carried by the 90 casing, a transparent plate adapted to cover the open front of the casing and engaging the inwardly extending flanges thereof, and a sliding plate received in the guide-way of the open end of the casing, said plate having an inwardly extending flange adapted to overlie the transparent plate at the open end of the casing for holding it within the casing.

3. A sign comprising a casing open at the front and one end, an inwardly extending flange formed around the top and bottom edges of the front opening and at the closed end, a guide-way formed at the open end of the casing, a reflector carried by the 100 casing with its outer edges spaced from the inwardly extending flanges formed around the top and bottom edges of the front opening and at the closed end, a transparent plate received in the casing between the outer edges of the reflector and the inwardly extending flanges, and a sliding plate received in the guide-way at the open end of the casing, said plate having an inwardly extending flange adapted to overlie the transparent plate at the open end of the casing for holding it within the casing.

In testimony whereof I hereunto affix my signature in the presence of two witnesses

EDWARD O. COTTON.
